UNITED STATES PATENT OFFICE.

EDGAR L. MORRIS, OF ST. LOUIS, MISSOURI, ASSIGNOR TO UNITED STATES SANITARY SPECIALTIES CORPORATION, OF CHICAGO, ILLINOIS, A CORPORATION OF ILLINOIS.

DESIGN FOR A LIQUID-SOAP DISPENSER.

56,079.

Specification for Design.

Patented Aug. 10, 1920.

Application filed December 9, 1919. Serial No. 343,609. Term of patent 14 years.

To all whom it may concern:

Be it known that I, EDGAR L. MORRIS, a citizen of the United States, residing at St. Louis, in the county of St. Louis and State of Missouri, have invented a new, original, and ornamental Design for Liquid-Soap Dispensers, of which the following is a specification, reference being had to the

accompanying drawing, forming part thereof, in which is illustrated in perspective a liquid-soap dispenser which exhibits my new design.

I claim:

The ornamental design for a liquid soap dispenser, as shown.

EDGAR L. MORRIS.
